UNITED STATES PATENT OFFICE.

JOHN R. TOWNSEND, OF SOUTH BEND, INDIANA, ASSIGNOR TO WESTINGHOUSE ELECTRIC & MANUFACTURING COMPANY, A CORPORATION OF PENNSYLVANIA.

DESIGN FOR A BEACON-LIGHT CASING.

Application filed February 20, 1926. Serial No. 16,602. Term of patent 14 years.

To all whom it may concern:

Be it known that I, JOHN R. TOWNSEND, a citizen of the United States, residing at South Bend, in the county of St. Joseph and State of Indiana, have invented a new, original, and ornamental Design for Beacon-light casings, of which the following is a specification, reference being had to the accompanying drawing, constituting a part hereof.

The figure is an elevational view of my

new design for a beacon-light casing, the dotted line portions being shown for the purpose of disclosing the manner in which the beacon-light casing is used.

I claim:

The ornamental design for a beacon-light casing, as shown.

In testimony whereof, I have hereunto subscribed my name this fifth day of February, 1926.

JOHN R. TOWNSEND.
